UNITED STATES PATENT OFFICE.

ERNST BÄCHLI, OF LAUFFOHR, NEAR BRUGG, SWITZERLAND.

BRAIDING MACHINE.

Application filed October 13, 1922. Serial No. 594,393.

To all whom it may concern:

Be it known that I, ERNST BÄCHLI, citizen of the Republic of Switzerland, residing at Lauffohr, near Brugg, Switzerland, have invented certain new and useful Improvements in Braiding Machines, of which the following is a specification, reference being had therein to the accompanying drawing.

The present invention relates to improvements in braiding machines provided with a jacquard mechanism. In the braiding machine according to the invention the drivers are arranged one beside the other around a circle and are not in direct operative connection with each other but each driver can be singly rotated by the action of an oscillating organ and in a direction that is opposite to the direction in which the adjacent drivers are rotated.

The intermeshing gear wheels which rotate the drivers constantly with other known types of braiding machines are done away with; only those drivers are rotated in the braiding machine, according to the invention, with which the spool carriers have to move at the time being, the other drivers standing still during that period. A braiding carrier is thereby practically prevented from moving along a wrong race way and a meeting of two braiding carriers or bobbins is prevented as the adjacent drivers rotate in opposite directions.

Two examples of the device according to the present invention are illustrated on the accompanying drawing, in which:

Fig. 1 shows in an elevation view and partly in a vertical section drivers and parts of the driving mechanism of one form of the braiding machine.

Fig. 2 is a vertical section along line II—II of Fig. 1,

Fig. 3 is a plan view partly in a horizontal section of the parts shown in Fig. 1,

Fig. 4 is a horizontal section along line IV—IV of Fig. 1,

Fig. 5 is a horizontal section along line V—V of Fig. 1,

Fig. 6 is an elevation view of the whole braiding machine showing the jacquard mechanism,

Figs. 7 and 8 are details of the jacquard mechanism,

Fig. 9 is a section along line IX—IX of Fig. 6,

Fig. 10 shows a modified construction in an

elevation and partly in a vertical section and

Fig. 11 is a plan view of Fig. 10, the race-way being omitted in the right hand part of the figure.

Referring to the example illustrated in Figs. 1—9, 1 denotes the base plate and 2 the race way consisting of an inner and an outer part arranged so as to form apertures in which the discs 3 of the drivers are located. 60 Bolts 4 are fixed to the base plate 1, the bolts being provided at their upper ends at 5 with screw threads, on which nuts 7 and antifriction balls 6 running on the upper surface of the discs 3 are arranged. The 65 lower part of each driver consists of a sleeve 8. The disc 3 of each driver is provided with two recesses 9 at its circumference serving to take up the spindle 10, onto which the spools or pirns are pushed in a known 70 manner. The recesses 9 on the circumference of a driver disc 3 are so shaped that two adjacent drivers can hold a braiding carrier between them and that the recesses together with the edges of the apertures in 75 the race way 2 form the guides for the braiding carrier when the latter is moved around the axis of a driver. The bolts 4 rest on the base plate 1 by means of a collar 11 which is preferably integral with the bolts. 80 The collar 11 is provided with two grooves 12 in which two vertical extensions 13 of a member 14 are guided. The member 14 is 85 slidable inside the sleeve 8 and is provided at its upper face with a cam surface. The 90 member 14 is further slidably arranged on the bolt 4, it can therefore be displaced in the axial direction but is prevented from carrying out a turning motion relatively to the bolt 4. The cam surface of the member 95 14 is provided with two elevations 16 and two depressions 17 and this cam surface is pressed by the action of the coil spring 15 against two pins 18 screwed radially into the sleeve 8. Upon a turning of the sleeve 8 the 100 pins 18 move along the cam surface, and as the sleeve 8 is secured against an axial displacement by the nuts 7 and the plate 1, the member 14 is reciprocated by the action of the pins 18 and the coil spring 15, the former 105 pressing the member 14 in the downward direction when the pins 18 move from a depression 17 to an elevation 16 and the coil spring 15 urges the member in the upward direction when the pins 18 move from an 110

elevation 16 to a depression 17 of the cam face.

Each sleeve 8 is further provided on its outer circumference with two radially projecting beaks or wing shaped extensions 19 and 20 situated near the base plate 1. The wings 19 and 20 appertaining to the drivers designated by uneven Roman figures in Fig. 3 are arranged at a higher elevation than the wings appertaining to the drivers designated by even Roman figures, so that the wings of adjacent sleeves 8 or drivers do not hinder each other in their turning movement, 21 and 22 are pins forming parts of a known jacquard mechanism which is illustrated in Figs. 6-9. The pins 21 and 22 act as stops to the wings 19 and 20 respectively and prevent a rotating movement of the drivers. 23 denotes a ring mounted in guides 24 to which ring an oscillating movement is imparted by means described hereinafter. The ring 23 is provided with projecting parts 26 (Figs. 2 and 3) which strike against the wings 19 or 20 when the latter are in suitable positions, the striking of a part 26 against a wing 19 or 20 initiates a turning movement of the sleeve 8, and the driver. As may be seen in Fig. 3 the pins 21 and 22 lock the wings 19 and 20 respectively of the bobbin heads II and III in such positions that the wings 19 and 20 do not project into the path of the parts 26 when the latter take part in the oscillating movement of the ring 23. When the stop pins 21 or 22 are withdrawn by the jacquard mechanism, the sleeve 8 will be turned to some extent by the action of the slightly compressed coil spring 15 causing an inclined portion of the cam surface to slide past the pins 18. Upon this slight turning movement of the sleeve 8 from the position shown for the driver III into the position of the driver I in Fig. 3, the wing 20 projects now into the path of the striker part 26 of the ring 23 and by the movement of ring 23 in one direction the striker part 26 engages with the wing 20 and turns the sleeve 8 of the driver to some extent in the direction indicated by the arrow in Fig. 3. Through this turning movement of the sleeve 8 the pins 18 wipe over an elevation 16 of the cam surface whereby the coil spring 15 is compressed; as soon as the elevation 16 is passed the compression of the spring 15 causes the inclined portion between the elevation 16 and the next depression 17 of the cam surface to slide past the pin 18 whereby a further turning motion of the sleeve 8 and thereby of the driver results. The striker parts 26 therefore only initiate the turning motion of the drivers and this motion is completed to half a turn by the action of the coil springs and the cam surfaces cooperating with the pins 18. The striker parts 26 are spaced along the ring

23 at such distance that every other driver (I, III, V) can be turned in one direction by the ring 23 moving in one direction of its oscillating motion whereas the intermediate drivers (II, IV, VI) are turned in the opposite direction when the ring 23 moves in the other direction. The control over the individual drivers which have to be operated in order to obtain a desirable braiding pattern is carried out by the jacquard mechanism by causing the withdrawal of the desirable stop pins 21, 22, which is carried out by the following means.

The stop pins 21 which cooperate with the drivers designated by uneven numbers in Fig. 3 are connected at their lower ends to pulling members 27 connected by means of bell crank levers 28, links 29, bell crank levers 30, pulling members 31 to the platines 32 which are in operative engagement with the lifting bar 33. Each stop pin 22 cooperating with a driver bearing a cam number in Fig. 3 is similarly connected by the parts 34, 35, 36, 37, 38, 39 to the lifting bar 40, (Fig. 6). 41 and 42 (Fig. 7) denote jacquard needles which are connected with the platines 32 and 39 respectively and which cooperate with the pattern-chain 43 provided with a number of apertures. The pattern-chain passes over and is intermittently moved by the turning motion of a member 44 of square cross-section. The member 44 is reciprocated in a horizontal guide 44' towards and away from the needles 41 and 42. When one of the needles enters into an aperture on the pattern-chain 43 the platine connected to said needle will be in such an operative position relatively to the corresponding lifting bar that it will take part in the upward movement of said bar, whereby the stop pin 21 or 22 respectively operatively connected to that platine will be withdrawn. Upon the downward movement of the lifting bar the stops 21 and 22 are returned into their raised positions by the action of the spring 21' and 22' respectively. When there is no aperture in the pattern chain at the point in which the needle abuts when the member 44 is moved towards the needle, the latter movement causes the needle to be pushed back, whereby the platine connected with said needle is brought out of operative engagement with the corresponding lifting bar and the stop pin 21 or 22 respectively remains in its operative position locking the driver.

The reciprocating movement of the lifting bar 33 is obtained in the following manner: A horizontal shaft 45 (Figs. 8 and 9) is rotated by means of bevel gearing 46 by the vertically disposed main driving shaft 47 on which a belt pulley 48 is fixed. Two cams 49 and 50 are fixed to the shaft 45, cam 49 cooperates with a rocking lever 51 the movement of which is transmitted to the lifting

bar 33 by means of links, 52 and 53 and bell crank lever 54. In a similar manner the reciprocating movement of the lifting bar 40 is derived from cam 50 by the interposition 5 of rocking lever 55, links 56 and 57 and bell crank lever 58. Further an eccentric 59 is fixed to the shaft 45 and the eccentric movement is transmitted by means of rod 60, rocking lever 61 and link 62 to the member 10 44 causing its reciprocating movement along the guide 44'. The turning motion of the member 44 is obtained by means of sprocket wheel 63 (Fig. 6) cooperating with a pawl 64 every time the member 44 is moved away 15 from the needles.

It will thus be seen that all the stop pins 21 can be operatively connected to the lifting bar 33 and can be simultaneously withdrawn whereas all the stop pins 22 can be 20 simultaneously operated by the lifting bar 40, the actually operative drivers depending on the apertures in the pattern chain. Upon the oscillating movement of the ring 23 in one direction every other driver will be rotated and the movement of the ring 23 in 25 the other direction will cause the rotation of the intermediate drivers. The means to impart the oscillating movement to the ring 23 are illustrated in Fig. 9 and consist of a 30 crank 65 fixed to the upper end of shaft 47, the crank pin 66 being connected by a link 67 to an eye 68 of the ring 23.

Upon the alternate turning motion of one series of the drivers in one direction and 35 thereafter of the other series of the drivers in the other direction the braiding carriers are transferred from one driver to the adjacent one and wander in a sinuous path around the centre of the braiding machine. 40 Thereby the threads from the spools are braided at the braiding point 69. The braided fabric is wound around a core 70 and the finished fabric is continuously pulled off that core by the known mechanism illustrated in Figs. 6 and 9 and finally wound on 45 a reel 71.

In Figs. 10 and 11 a modification to the device for effecting the turning of the drivers is shown. The sleeve 8 carrying the driving discs 3 of the driver is rotatably mounted on a hollow bolt 4 fixed to the base plate 1 of the machine. Instead of the member 14 provided with a cam surface at its upper end a cam 14' is provided integral 50 with the sleeve 8. Two levers 72 and 73 are turnably mounted on the set screw 74 acting as fulcrum. The free ends of said levers carry antifriction rollers 75 and 76 respectively which cooperate with the cams 14' of two adjacent drivers. A compression spring 77 common to both levers 72 and 73 is inserted between extensions 78 and 79 of 55 said levers and urges both rollers 75 and 76 against the faces of the cams 14'. The cam 14' is provided with two elevations 16 and

two depressions 17 in a similar manner as the cam surface of the member 14 in the form illustrated in Fig. 1 and the effect of the rollers on the cam under the action of the spring is similar to the action of the 70 cam surface of member 14, pins 18 and spring 15 in the form shown in Fig. 1 and causes a turning of the driver after the turning movement has been initiated. The means for initiating said turning movements 75 of the driver show some modifications as compared with the means provided in the first example. Instead of the oscillating ring 23 a toothed rim 80 is utilized to which an oscillating movement is imparted by the 80 link 67. Four wings 81 of small height are provided and shaped to form teeth which are adapted to cooperate with the teeth of the rim 80 and form together a pinion of a square shape when seen in plan view. Two 85 of said teeth lying diametrically opposite each other are provided with downwardly extending lugs 82 for engagement with the jacquard stop pins 21 and 22 respectively. When the latter are withdrawn the roller 75 90 causes the cam to turn through a small angle until the roller has reached the depression 17 of the cam. When this is the case the driver will be in an angular position shown by the third driver in Fig. 11. In this position one of the tooth shaped wings 82 projects into the path of the toothed rim 80 and will mesh with a tooth of the latter when the rim oscillates in the direction of the arrow 95 shown in Fig. 11. The driver will then be turned and the cam 14' causes the roller 75 to carry out a turning movement about the fulcrum 74 of the lever 72. As the roller 76 of the lever 73 abuts against the cam 14' of the adjacent driver which is prevented 100 from carrying out a turning movement by the stop pin 22, which is not withdrawn, the spring 77 is compressed. As soon as the turning motion of the driver through the medium of the toothed rim 80 has been carried so far that the roller 75 has passed the 105 elevation 16 of the cam, the driver will be further turned by the action of the roller 75 on that cam. Every alternate driver will be turned in one direction when the toothed rim 80 oscillates in one direction and the other drivers will be turned thereafter in the other direction when the toothed rim 80 oscillates in the other direction, and when all the stop pins 21 are simultaneously withdrawn by the jacquard mechanism previous to the turning motion in one direction and when all the stop pins 22 are withdrawn previous to the turning motion in the other direction by a jacquard mechanism of the same type as has 110 been described hereinbefore.

I claim:

1. A braiding machine comprising in combination, a base plate, a plurality of drivers rotatably mounted on said base 115

plate and spaced around a circle, a cam on each driver, a roller cooperating with said cam, a spring pressing said roller against said cam and adapted to cause thereby a turning motion of the driver, oscillating means adapted to impart to each driver of a group comprising every alternate driver an intermittent turning motion in one direction and to impart to each driver of a group comprising every driver intermediate to the drivers of the first group an intermittent turning motion in the other direction, said turning motion being completed to a desired extent by the action of said cam, roller and spring arrangement, a jacquard mechanism, and means operated by said jacquard mechanism to cause a number of individual drivers to come into operative connection with said means for imparting intermittent rotation to the drivers, the selection of the operative drivers being controlled by a pattern chain of the jacquard mechanism.

2. A braiding machine comprising in combination, a base plate, a plurality of drivers rotatably mounted on said base plate and spaced around a circle, a cam on each driver, a roller cooperating with said cam, a spring pressing said roller against said cam and adapted to cause thereby a turning motion of the driver, oscillating means adapted to impart to each driver of a group comprising every alternate driver an intermittent turning motion in one direction and to impart to each driver of a group comprising every driver intermediate to the drivers of the first group an intermittent turning motion in the other direction, said turning motions being completed to a desired extent by the action of said cam, roller and spring arrangement, a jacquard mechanism, projections provided on said drivers, and a displaceable stop pin to each driver cooperating with said projections and operatively connected to said jacquard mechanism, the displacement of said stop pins causing the respective drivers to come into operative connection with said oscillating means for imparting intermittent rotation to said drivers.

3. A braiding machine comprising in combination, a base plate, a plurality of drivers rotatably mounted on said base plate and spaced around a circle, a cam on each driver, a roller cooperating with said cam, a spring pressing said roller against said cam and adapted to cause

thereby a turning motion of the driver, a toothed rim, means to oscillate said toothed rim, teeth provided on each driver adapted to be brought in and out of mesh with said toothed rim so that to each driver of a group comprising every alternate driver an intermittent turning motion in one direction may be imparted when said toothed rim oscillates in one direction and to each driver of a group comprising every driver intermediate to the drivers of the first group an intermittent turning motion in the other direction may be imparted, said turning motion being completed to a desired extent by the action of said cam, roller and spring arrangement, a jacquard mechanism, and means operated by said jacquard mechanism to cause a number of individual drivers to come into operative connection with said means for imparting intermittent rotation to the drivers, the selection of the operative drivers being controlled by a pattern chain of the jacquard mechanism.

4. A braiding machine comprising in combination, a base plate, a plurality of drivers rotatably mounted on said base plate and spaced around a circle, a cam on each driver, a roller cooperating with said cam, a spring pressing said roller against said cam and adapted to cause thereby a turning motion of the driver, a toothed rim, means to oscillate said toothed rim, teeth provided on each driver adapted to be brought in and out of mesh with said toothed rim so that to each driver of a group comprising every alternate driver an intermittent turning motion in one direction may be imparted when said toothed rim oscillates in one direction and to each driver of a group comprising every driver intermediate to the drivers of the first group an intermittent turning motion in the other direction may be imparted, said turning motion being completed to a desired extent by the action of said cam, roller and spring arrangement, a jacquard mechanism, projections provided on said drivers, and a displaceable stop pin to each driver cooperating with said projections and operatively connected to said jacquard mechanism, the displacement of said stop pin causing the respective drivers to come into operative connection with said oscillating means for imparting intermittent rotation to said drivers.

In testimony whereof I affix my signature.

ERNST BÄCHLI.
